his Attorney.

UNITED STATES PATENT OFFICE

JOSEPH B. KAUSÄL, OF CHICAGO, ILLINOIS

WALL LIGHT

Application filed June 18, 1928. Serial No. 286,160.

This invention relates to wall lights and more particularly to a wall light adapted to use in corridors, hallways, stairways, and similar places where a limited amount of illumination is desired and is preferably confined to the floor area. An object of the invention is the provision of a light of this character in which the source of light will be effectually concealed and in which the projection of the device from the wall is reduced to a minimum. As a more specific object, the device of the invention provides a hall light imbedded within the wall structure, so constructed and arranged as to prevent glare and produce a soft diffusion of light, the source of light being invisible or concealed when viewed at any angle except directly.

Other objects will appear hereinafter.

The invention consists in the combinations and arrangements of parts hereinafter described and claimed.

The invention will be best understood by reference to the accompanying drawings forming a part of this specification and in which;

Fig. 1 is a front elevation of a portion of a wall showing the device of the invention mounted in operative position;

Fig. 2 is a vertical section through the wall shown in Fig. 1 and showing the manner in which the device is imbedded into the wall structure;

Fig. 3 is an enlarged face view of the device with the front cover plate removed showing the lamp mounted in position;

Fig. 4 is a vertical sectional view taken on the line 4—4 of Fig. 3;

Fig. 5 is a perspective view of the light directing member;

Fig. 6 is a perspective view of the lamp bracket; and

Fig. 7 is a sectional view through the main socket member.

As illustrated in the drawings, the preferred embodiment of the invention comprises a casing 10, upon the open side of which are laterally extending inturned flanges 11 having threaded openings 12. A bracket 13 for mounting the lamp preferably is provided

with a base portion 14 and a socket receiving portion 15 disposed at right angles to the base portion and provided with a circular opening 16 for reception of the lamp socket. The bracket 13 is preferably secured to the rear wall 17 of the casing 10 by means of small screw bolts 19 extending through openings 18 in bracket 13 into screw threaded or other suitable openings provided therefor in the back plate 17.

The device is preferably mounted within the wall in such manner that the forward edge of casing 10 and the two lateral flanges 11 are substantially flush with the surface of plaster 20 or other wall covering, and provision for mounting is made in the form of openings 21 upon the back plate 17 whereby the device may be directly nailed or screwed to the studding or through which metal straps 22 may be bolted in adopting the mounting shown in Fig. 2, in which the straps 22 are bent at right angles for securing to the studding. The front cover plate 23 is removably secured to the casing 10 in any approved manner such as by small screw bolts threaded into the openings 12 and, as will be noted, the cover plate has a flat surface, except for a substantially rectangular hood portion 24 extending downwardly and slightly outwardly, and disposed at an angle with reference to the main flat portion of the cover plate. In pressing out the hood portion 24, end portions 25 are formed which further serve to confine the distribution of light and there is also formed a rectangular opening into which is fitted the light directing member 26 in such manner as to be oppositely disposed with reference to the flat portion of the cover plate at substantially the same angle as the hood portion 24. Member 26 is preferably provided with a series of parallel vanes or louvers 27 for the purpose of directing the rays of light, and the light directing member 26 is secured to the cover plates by rivets 28. Further, in forming the cover plate 23 the edges are preferably beveled to improve the appearance and small depressions are formed at the screw holes so that the screw bolt heads

will be countersunk and become flush with the cover surface.

The lamp socket consists of two pieces which are screwed together through the opening 16 of the bracket 13 and the base member 29 is provided with a projecting lug 30 which fits into notch 31. As shown in Fig. 4, the lamp 35 and bracket are disposed slightly above the level of the light openings between the vanes 27, and in this adjustment the light is confined to a relatively small area adjacent the wall, but a satisfactory provision for increasing the extent of light may be had by providing additional screw threaded openings 32 for securing the lamp bracket in a lower position. The casing 10 is provided with a plurality of knock-outs 33 disposed so as to render connection with the conduit 34 convenient from any direction.

The device of the invention is conveniently accessible and furnishes the desired amount of illumination in the locations indicated while the source of light is concealed and the device occupies a minimum of space in front of the wall. When the device is located at the head of a stairway, for example, the vanes 27 effectually shield the rays of light and prevent glare to a person ascending the stairs, and these vanes further serve to confine the illumination to a definite area in advance of the wall upon which the device is mounted without casting shadows.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

What I claim is new and desire to secure by Letters Patent is:

1. A wall light of the flush type adapted to be imbedded in a building wall structure, comprising a casing having an open side, a lamp mounted within said casing, a closure plate for the open side of said casing and adapted to extend vertically with the edges substantially flush with the wall surface, said closure plate having an outwardly pressed portion arranged to form a downwardly and outwardly inclined light directing hood and the frame of a substantially rectangular light emitting opening, the remaining face of said plate being substantially flat, said light emitting opening extending substantially from the face of said closure plate to the forward edge of said hood, a plurality of parallel louver members disposed transversely across said opening to conceal the source of light when viewed at any angle except directly, and means for attaching said casing to said wall structure rearwardly of said wall surface.

2. A wall light of the flush type adapted to be imbedded in a building wall structure, comprising a casing having an open side, a lamp mounted within said casing, a closure plate for the open side of said casing and adapted to extend vertically with the edges substantially flush with the wall surface, said closure plate having an outwardly pressed portion arranged to form a downwardly and outwardly inclined light directing hood and the frame of a substantially rectangular light emitting opening, the remaining face of said plate being substantially flat, said light emitting opening extending substantially from the face of said closure plate to the forward edge of said hood, a plurality of parallel louver members disposed transversely across said opening to conceal the source of light when viewed at any angle except directly, said louvers extending substantially at the same angle from said closure plate as the hood but in a reverse direction, and means for attaching said casing to said wall structure rearwardly of said wall surface.

In testimony whereof I have signed my name to this specification.

JOSEPH B. KAUSAL.
